AUTOMATIC FIREARM

George Norman, Birmingham, England, assignor
to Auto-Ordnance Corporation, New York,
N. Y., a corporation of New York

Application June 5, 1934, Serial No. 729,052

7 Claims. (Cl. 42—69)

While the invention herein described and claimed is applicable to a great variety of firearms it is particularly applicable to automatics (semi-automatic and/or full-automatic) of the type in which the receiver is open at the bottom and the frame which carries the fire-control mechanism telescopes over the open bottom from the rear, the upper side of the frame being open to permit interengagement between the fire-control mechanism and the breech-closing mechanism as in the patent to Eickhoff No. 1,437,889, granted December 5, 1922.

Objects of the invention are to provide improved means for holding the frame on the receiver and an improved cooperative relationship between the mechanisms carried in the receiver and frame respectively. More particularly the invention affords fire-control mechanism which has fewer parts, which is more reliable and durable in use and which can be assembled and disassembled with greater facility.

In the aforesaid patent the sear is made in two parts, one of which engages the bolt and the other of which is actuated by the trigger through the medium of a disconnector pivotally mounted on the trigger, and another part called a rocker is arranged to disengage the disconnector from the sear when the bolt advances. A trip is also provided to disengage the disconnector from the sear when the last cartridge leaves the magazine.

According to the present invention the fire-control mechanism differs from the aforesaid construction in one or more of the following characteristics. Instead of forming the sear in two parts it comprises a single part. The separate rocker for actuating the disconnector in the forward movement of the bolt is eliminated, the disconnector being actuated directly by the bolt. Instead of pivoting the disconnector on the trigger it is pivoted on the frame of the gun. The disconnector is pivoted on the same pin as the trip, thereby eliminating another pivot pin. And instead of the sear being controlled by the trip through the medium of the disconnector the sear is controlled by the disconnector through the medium of the trip. Obviously these characteristics may be used independently or in various sub-combinations without using them all together as in the preferred embodiment.

For the purpose of illustration a typical embodiment of the invention is shown in the accompanying drawings in which,

Fig. 1 is a top plan view of the frame of the gun removed from the receiver;

Fig. 2 is a vertical longitudinal section through

the frame and receiver showing the bolt in retracted position and the firing mechanism set for semi-automatic operation;

Fig. 3 is a similar view showing the parts set for similar operation but with the bolt moving forward;

Fig. 4 is a similar view showing the firing mechanism set for full-automatic operation;

Fig. 5 is a side elevation of the trip-disconnector assembly viewed from the opposite side to that shown in Figs. 2, 3 and 4;

Fig. 6 is a side view of the pivot pin for the disconnector and trip;

Fig. 7 is an end view of the pivot pin;

Fig. 8 is a side view of the sear viewed from the same side as in Figs. 2, 3 and 4; and

Fig. 9 is a bottom plan view of the sear.

The particular embodiment of the invention chosen for the purpose of illustration comprises a receiver 101, a bolt 108 movable back and forth in the receiver and a frame 105 detachably connected to the under side of the receiver by means of inwardly extending lips 1 which slide in grooves in the sides of the receiver 101, the frame sliding onto the receiver from the rear and being held in normal position by means of a catch 2 pivoted in the frame by means of a pin 3 and urged to latching position by spring 4. To release the frame from the receiver the catch 2 is swung in a clockwise direction by means of a plunger 5 which is prevented from dropping out when the gun is inverted by means of a pin 6 extending through a recess 7 in the side of the plunger. The mechanism for automatically locking the bolt in breech-closing position and unlocking the bolt in response to the breech pressure may be substantially like that disclosed in the aforesaid patent and therefore need not be described herein.

In general the fire-control mechanism, comprising the subject-matter of the present invention, comprises a sear 8 pivoted in the frame at 9, a trigger 10 pivoted on the pin 3 for swinging the sear in a clockwise direction to release the bolt through the medium of a trigger bar 11 pivotally connected to the trigger at 12 and having a shoulder 13 for engagement with the depending portion 14 of the sear. To lock the sear in safe position a pin 15 is journaled in the frame with a handle 16 on the left-hand side of the frame to swing the pin through 180°. The pin 15 has a cut-away portion 17 underlying the rearwardly extending portion 18 of the sear so that when the pin is in the position shown in Figs. 1 to 4 inclusive the sear may be actuated to release the

bolt but when the safety pin 15 is rotated through 180° the actuation of the sear is blocked by the pin.

To disengage the trigger bar 11 from the sear 8 when the last cartridge leaves the magazine a trip 19 is pivoted on the portion 20 of a pin 21 which is journaled in the opposite side walls of the frame 105, the trip being urged in a counterclockwise direction by a spring 29. The trip 19 has a rearward portion 22 engaging the forward end of the trigger bar 11 so that when the trip is rotated in clockwise direction around the pin 21 the shoulder 13 of the trigger bar is moved out of engagement with the sear to permit the sear to be returned to bolt-holding position by the sear spring 23 seating in a recess 27 in part 28 of the sear. The forward end 24 of the trip 19 extends into the path of a lug 25 on the magazine follower 26 so that when the last cartridge leaves the magazine the lug 25 swings the trip in clockwise direction to disengage the trigger bar from the sear.

For semi-automatic operation the gun is provided with a disconnector 30 which is pivoted at its forward end on the eccentric portion 41 of the pin 21 and which has at its rearward end a slot 32 into which a pin 33 projects from the right-hand side of the trip 19. Above the slot 32 the disconnector is provided with a convex cam surface 34 which, when the gun is set for semi-automatic operation, projects into the path of the bolt so that when the bolt moves forward it depresses the rearward end of the disconnector, swinging it in a clockwise direction about the pivot 31, thereby also swinging the trip 19 in a clockwise direction to disengage the trigger bar from the sear by virtue of the engagement of the upper edge of the slot 32 with the pin 33. To move the disconnector to full-automatic position the handle 35 of the pivot pin 21 is swung from the position shown in Fig. 1 downwardly through 180° to a position where the handle 35 extends rearwardly instead of forwardly from the pivot pin. Inasmuch as the eccentric portion 31 of the pivot pin 21 extends from the axis of the pin in the same direction as the handle 35 the disconnector is moved to the rear when the handle 35 is swung from semi-automatic position to full-automatic position, and in this rearward movement of the disconnector the rear portion of the disconnector is moved downwardly by engagement of the under side of the slot 32 with the pin 33, thereby removing the convex cam surface 34 from the path of the bolt.

The operation of the firearm is as follows: For semi-automatic operation the handle 35 of the disconnector pivot pin 21 is set in the position shown in Figs. 1, 2 and 3. Thus, when the bolt is retracted and the trigger released the parts are in the position shown in Fig. 2. When the trigger is retracted the bolt is advanced by the recoil spring 36 and when the bolt reaches the position shown in Fig. 3 it engages the cam surface 34 to swing the disconnector 30 in a clockwise direction about the pivot 31, the upper edge of the slot 32 of the disconnector pressing downwardly on the pin 33 carried by the trip 19 to swing the trip 19 in a clockwise direction and this in turn disengages the trigger bar 11 from the sear 8 by virtue of the interengagement between the portion 22 of the trip and the forward end of the trigger bar. Thus when the bolt recoils to retracted position the sear 8 is free to be returned to the bolt-holding position shown in Fig. 2 by the sear spring 23. For full-automatic operation the handle 35 is

swung to the rear to depress the rearward end of the disconnector out of the path of the bolt as shown in Fig. 4. In this position of the disconnector the trigger bar is not disengaged from the sear when the bolt moves forwardly and consequently the gun will fire repeatedly, either until the trigger is released or until the lug 25 on the magazine follower engages the forward end of the trip 19 when the magazine becomes empty.

It should be understood that the present disclosure is for the purpose of illustration only and that this invention includes all modifications and equivalents which fall within the scope of the appended claims.

I claim:

1. An automatic firearm comprising a frame, a bolt, a sear, trigger means for disengaging the sear from the bolt, a pivoted trip for disengaging the trigger means from the sear, a pivoted disconnector responsive to movement of the bolt for disengaging the trigger means from the sear, and a common pivot pin for said trip and disconnector. 20

2. An automatic firearm comprising a frame, a bolt, a sear, trigger means for disengaging the sear from the bolt, a pivoted trip for disengaging the trigger means from the sear, a pivoted disconnector responsive to movement of the bolt for disengaging the trigger means from the sear, a common pivot pin for said trip and disconnector, 25 the disconnector being mounted on an eccentric portion of said pin, and a handle outside the frame for rotating the pin to move the disconnector out of the path of the bolt for full-automatic operation. 30

3. An automatic firearm comprising a frame, a bolt, a sear, trigger means for disengaging the sear from the bolt, a pivoted trip for disengaging the trigger means from the sear, a pivoted disconnector responsive to movement of the bolt 40 for disengaging the trigger means from the sear, and a common pivot pin for said trip and disconnector, the disconnector being mounted on an eccentric portion of said pin and having a camming interconnection with the trip so that when 45 the pin is rotated back and forth the disconnector is moved into and out of the path of the bolt.

4. An automatic firearm comprising a frame, a magazine, a bolt, a sear, trigger means for disengaging the sear from the bolt, a trip pivoted 50 on said frame for disengaging the trigger means from the sear, and a disconnector responsive to movement of the bolt for actuating said trip, said trip having an integral portion actuated directly by the magazine when the last cartridge leaves 55 the magazine.

5. An automatic firearm comprising a frame, a magazine, a bolt, a sear, trigger means for disengaging the sear from the bolt, a pivoted trip for disengaging the trigger means from the sear, 60 a pivoted disconnector responsive to movement of the bolt for causing the trip to disengage the trigger means from the sear, a common pivot pin for said trip and disconnector, and means for actuating the trip when the magazine is 65 emptied.

6. An automatic firearm comprising a frame, a magazine, a bolt, a sear, trigger means for disengaging the sear from the bolt, a pivoted trip for disengaging the trigger means from the sear, 70 a pivoted disconnector responsive to movement of the bolt for disengaging the trigger means from the sear, a common pivot pin for said trip and disconnector, the disconnector being mounted on an eccentric portion of said pin, and a 75

handle outside the frame for rotating the pin to move the disconnector out of the path of the bolt for full-automatic operation, a common pivot pin for said trip and disconnector, and means for actuating the trip when the magazine is emptied.

7. An automatic firearm comprising a frame, a magazine, a bolt, a sear, trigger means for disengaging the sear from the bolt, a pivoted trip for

disengaging the trigger means from the sear, a pivoted disconnector responsive to movement of the bolt for disengaging the trigger means from the sear, and a common pivot pin for said trip and disconnector, said trip having a portion actuated by the magazine when the last cartridge leaves the magazine. ⁵

GEORGE NORMAN.
